UNITED STATES PATENT OFFICE.

MAX KURTH, OF WALDRON, ARKANSAS.

EVAPORATING-PAN.

1,240,984.

Specification of Letters Patent. Patented Sept. 25, 1917.

Application filed October 21, 1916. Serial No. 126,976.

To all whom it may concern:

Be it known that I, MAX KURTH, a citizen of the United States, residing at Waldron, in the county of Scott and State of Arkansas, 5 have invented certain new and useful Improvements in Evaporating-Pans, of which the following is a specification.

My invention relates broadly to evaporators, and more particularly to a class of 10 evaporators for drying fruits and vegetables by means of a steam application.

The present invention has as its principal aim and object to provide novel means for supporting the drying pan on the boiler, and 15 to provide the drying pan with novel means to permit of the escape of steam from the boiler.

As an additional object and one of equal 20 importance as the first mentioned object, the invention provides novel means for movably connecting and supporting the boiler, forming a part of the evaporator, on the top of the stove so that the boiler can be swung from a transverse position over the fire box 25 on the top of the stove to a position longitudinally of the top of the stove, the latter incidentally, being provided with coöperating receiving means for the supporting means to consequently allow the boiler to 30 rest flat on the stove when in either of its adjusted positions.

As a further improvement, the invention embraces the provision of means for facilitating the movement of the boiler as well 35 as means for facilitating the removal of the pan from the boiler.

Among the other aims and objects of the invention may be recited the provision of a device of the character mentioned, with a 40 view to compactness, and in which the number of parts are few, the cost of production low, and the efficiency high.

Other objects as well as the nature and characteristic features of my invention will 45 be apparent from the following description taken in connection with the accompanying drawings, and more particularly pointed out in the appended claims.

The preferred embodiment of the invention 50 is illustrated in the accompanying drawings in which:—

Figure 1 is a top plan of my invention.

Fig. 2 is an end elevation of my invention

in position over the fire box of a stove, the latter being shown partly in longitudinal 55 section.

Fig. 3 is a longitudinal section of my invention on the top of a stove, the latter being shown in transverse section.

Fig. 4 is a transverse section of my invention taken on line 4—4 of Fig. 3.

Fig. 5 is a perspective detail.

Referring now, more particularly, to the accompanying drawings in which similar reference numerals designate like and corresponding parts throughout the several views, I provide a stove including a body 1 having a top 2 provided with a plurality of lid openings 3 which are closed by lids 4 of any conventional type. As is usually 65 the case the openings are arranged in pairs longitudinally of the top, one pair of the openings as is obvious being arranged over the fire box 5 adjacent one end of the stove. A stud 6 is arranged perpendicularly of the 70 top of the stove adjacent the rear end and pivotally connected thereto so as to swing either transversely or longitudinally. On the top is my improved evaporator designated in its entirety by the numeral 7. In 75 the present instance the evaporator consists of a lower receptacle or boiler 8 preferably of a rectangular configuration. An ear 9 extends from one end of the boiler and serves as a means for pivotally connecting 80 the evaporator to the stove. Handles 9' of any conventional construction serve as means for moving the boiler, forming a part of the evaporator about the top of the stove.

A drying pan 10 is constructed similarly 90 to the boiler 8 though of a size slightly smaller and of depth of about one-half as great as the boiler. The upper edges of the ends of the pan 10 are flared to provide flanges 11 which rest on the edges of the 95 ends of the boiler 8 so as to support the bottom of the pan in spaced relation to the bottom of the boiler. Of course, the boiler receives a quantity of water to consequently generate steam when the device is arranged 100 over the openings which are in turn arranged over the fire box 5 and in order to allow this steam to escape, I have provided the sides of the pan with oppositely disposed vertically extending grooves 12 formed preferably by depressing the sides. Handles 13

of any conventional construction are rigidly connected to the flanges 11 so as to facilitate the removal of the pan.

With a view toward removably supporting the evaporator on the stove I have connected suitable casters to the outer or free lower end of the boiler. In the present instance the casters include rollers 14 which are rotatably mounted between the bifurcated ends of the shanks 15 the latter in turn being carried in the bracket 16 which are connected to the boiler. As is apparent the rollers are arranged in a plane below the bottom of the boiler so as to support the bottom in spaced relation to the top of the stove while it is being moved. Incidentally, the top of the stove is provided at one side adjacent the fire box end with suitable receiving means which consists of spaced recesses 17 formed preferably by depressing the top. Similarly constructed spaced recesses 18 are also formed at the opposite end of the top of the stove and adjacent the opposite side as indicated in Fig. 1 of the drawings. These recesses 17 and 18 are engageable by the rollers when the evaporator has been swung into adjustable position to allow the bottom of the boiler of the evaporator, to lie flat on the top of the stove. It is to be appreciated that the boiler can be used for preserving fruit in the usual manner and in Fig. 5 I have illustrated a wire receptacle 19 having a bail 20 connected thereto. This receptacle is adapted to receive suitable preserving jars (not shown) so that the jars can be properly heated by placing the receptacle within the boiler preparatory to filling the jars with fruit that has previously been prepared in the boiler.

The operation of the present invention may be reviewed as follows:—

After the boiler 8 has been partially filled with water the drying pan 10 is arranged in its proper position on the upper edge of the boiler and suitable fruit or vegetables are now properly prepared and arranged in the pan, whereupon the handles 9' are engaged and the boiler is lifted from the recesses 17 and swung from a position indicated by the dotted lines in Fig. 1 about the top of the stove to a position transversely of the top directly over the fire box 5 of the stove. It is to be appreciated that the rollers facilitate the movement of the evaporator about the stove and incidentally are received in the recesses which permit of the bottom of the boiler contacting with the stove and also prevent accidental displacement of the evaporator from the stove.

The water in the boiler is heated to a boiling point and generates steam which sufficiently heats the drying pan to efficiently dry the fruit or vegetables therein. The steam escapes from the grooves 13 to a point remote from the boiler. It is to be appre-

ciated that the evaporator can be swung back to its former position and the drying pan removed by engaging the handles.

As many changes could be made in the above construction and many apparently widely different embodiments of this invention could be made without departing from the scope thereof, it is intended that all matter shown in the accompanying drawings shall be interpreted as illustrative and not in a limiting sense. It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent is:—

1. The combination with the top of a stove, of a boiler pivotally connected to the top and arranged to be swung either longitudinally or transversely thereof, and means for rotatably supporting the outer free end of the boiler during movement.

2. The combination with the top of a stove, of a boiler pivotally connected to the top and arranged to be swung to a position either longitudinally or transversely thereof, means for rotatably supporting the outer free end of the boiler during movement, and a drying pan receivable within the boiler and supported on the upper edge of the latter and provided with means to permit of the escape of steam from the boiler.

3. The combination with the top of a stove having the usual openings therein and provided with spaced notches thereon, of a boiler pivotally connected to the top of the stove, means for movably supporting the boiler in spaced relation to the side of the stove and allow the boiler to be moved thereover, said means being adjustable in said notches, and a drying pan supported on and receivable within the boiler and provided with means for preventing the escape of steam therefrom.

4. The combination with the top of a stove having spaced recesses arranged at one end and adjacent one side and also at the opposite side and adjacent the opposite end, of a boiler pivoted to one end of the top of the stove and adapted to be swung into position either transversely or longitudinally thereof, and casters connected to the outer free end of the boiler for supporting the bottom of the boiler in spaced relation with the top during movement and adapted to engage either of the spaced recesses and allow the bottom of the boiler to rest on the top of the stove.

5. An evaporator including a boiler adapted to have one end thereof pivotally

connected to the top of a stove, and having rollers mounted thereon for engagement with the top of a stove to facilitate its movement thereover.

- 5 6. An evaporator including a boiler, a drying pan adapted to fit within the boiler and having the side walls thereof to engage the walls of the boiler, said pan being supported from the upper edge of said boiler

and having depressions in the side walls 10 thereof forming passages to permit the escape of steam from the boiler.

In testimony whereof I affix my signature in presence of two witnesses.

MAX KURTH.
